UNITED STATES PATENT OFFICE

99,478

DESIGN FOR A HANDBAG

Abraham Kulick, New York, N. Y.

Application January 30, 1936, Serial No. 60,891

Term of patent 3½ years

To all whom it may concern:

Be it known that I, Abraham Kulick, a citizen of the United States, residing at New York, in the county of New York and State of New York, have invented a new, original, and ornamental Design for Handbags, of which the following is a specification, reference being had to the accompanying drawing, forming part thereof.

I claim:

The ornamental design for a handbag, as shown and described.

ABRAHAM KULICK.
